UNITED STATES PATENT OFFICE.

EMILE D. KRIEG, OF NEW YORK, N. Y.

VENTILATOR FOR TYPE-CASTING MACHINES.

Application filed October 14, 1922. Serial No. 594,547.

To all whom it may concern:

Be it known that I, EMILE D. KRIEG, a citizen of the United States of America, residing at New York city, in the county of 5 New York and State of New York, have invented certain new and useful Improvements in Ventilators for Type-Casting Machines, of which the following is a specification.

10 My invention relates to a ventilator for type-casting machines, and particularly for the ventilation of the melting pot. The object of my invention is to provide an improved ventilator having certain characteristics hereinafter described or shown in the accompanying drawings, in which—

Fig. 1 is a schematic view of an installation in which my invention is embodied;

Fig. 2 is a broken section drawn to a 20 larger scale through a melting pot showing my improved ventilator applied thereto;

Figs. 3 and 4 are sections on the lines 3—3, 4—4, Fig. 2 respectively, drawn to a larger scale; and

25 Fig. 5 is a perspective of the locking ring. In the operation of type-casting machines, it is common practice to melt the type metal in a pot mounted on the machine and heated by a gas burner. The metal fumes rising 30 from the pot, as well as the products of combustion from the gas burner are both commonly discharged into the atmosphere of the composing room, constituting a menace to the health of the operatives. It 35 has been proposed to carry off these objectionable gases through venting flues, but the constructions employed for this purpose have been of rather crude and defective character. The present invention provides 40 improved arrangements for this purpose.

As illustrated in the accompanying drawings, the melting pot 6 is provided with a surrounding jacket 7 slightly spaced therefrom to permit the heat from the gas burner 45 8 to surround the pot and keep the metal 9 therein in molten condition. At one end the jacket is extended and provided with an upwardly extended nipple 10 ported at 11 to vent the products of combustion from the 50 gas burner. A hollow standard 12 is sleeved upon the nipple 10 and leads the products of combustion from the gas burner upward therethrough to a ventilating duct 13. Where a number of machines are arranged 55 in a single room, the ventilating system may comprise a series of pipes 14, 15, 16 and 17

connected together by tapered Y-joints 18, 19 and 20, the pipes 14—17 being graduated to afford a stepped-up increase of volumetric capacity as they approach the exhaust 60 fan 21 which delivers to a discharge pipe 22.

Mounted at the head of the standard 12 of each melting pot is a coned ventilating head 23 laterally apertured by three ports 24, of which two are preferably oval and one 65 round. Swivelling thereon is a correspondingly shaped sleeve 25 at the upper end of a conduit 26 adapted to be arranged over the melting pot and having a vertically adjustable sleeve 27 normally lowered into 70 juxtaposition to the surface of the molten metal and serving to collect the fumes rising therefrom. In operating position the conduit communicates with the ventilating head through one or other of the ports 24. 75

Inasmuch as the metal 9 is constantly drawn off during the operation of the type-casting machine, it is necessary to frequently replenish the supply of metal in the pot. This is commonly done by dropping into the 80 pot pigs of type metal. In order that this may be readily accomplished, I provide the sleeve 27 with a handle 27^a, by which the operative may readily lift it out of obstructing position. It is desirable in some instances to hold the sleeve up to permit skimming of dross or any impurities off the molten metal. For this purpose the upper end of the sleeve is provided with a hook 27^b which may be engaged on a stud 27^c on 90 the conduit, by rotating the sleeve slightly in raised position.

It is also desirable when cleaning the machine or making adjustments in the neighborhood of the pot, to get the conduit 95 out of the way, so that it is not necessary to lower the pot to render these operations possible. For this purpose I provide a connection between the conduit 26 and the ventilating head 23 of such character that the 100 former may be temporarily moved from obstructing position. The sleeve 25 has a swivelling engagement with the coned head 23 on the standard 12. In order to prevent leakage at this swivel joint, which might 105 undesirably affect the ventilation system, I provide a locking ring 28, upon the plane upper surface of which the lower margin of the sleeve 25 is supported. The lower face of the ring 28 is provided with cam 110 surfaces 29 which rest upon supporting studs 30 projecting from the neck 31 of the head

23. Upon the rotation of the ring 28 by means of its handle 32, the sleeve 25 is lowered and thus freed from engagement with the coned head 23. The conduit 26 and its sleeve may then be freely swung around by the operative, by means of the handle 33, until it is out of obstructing position. Upon the return of the conduit to its normal position, the handle 32 of the locking ring 28 is rotated in reverse direction, and the cam faces 29 of the ring, riding the fixed studs 30, lift the ring and thus the sleeve 25 into close engagement with the ventilating head 23. The joint between these parts is thus sealed and the position of the conduit above the top of the melting pot is maintained regardless of the vibrations to which the machine is subjected during its operation.

20 If it be desired to regulate the pull of the exhaust fan in each ventilating flue, this may be readily accomplished by arranging dampers 34 and 35 in the standard 12 and in the conduit 26. The adjusted position 25 of these dampers may be fixed by set screws 36 passing through arcuate slots in segments 37 at the outer ends of the damper spindles 38. It may be pointed out that the set 30 screws serve to hold the damper spindles in position, as well as fixing the angular position of the damper. It may be also pointed out that the damper itself may be introduced through one of the oval shaped 35 ports 24 in the ventilating head after the sleeve has been removed—and without necessitating a complete dismantling of the installation to effect this repair.

While I have shown a construction in which the pot 6 is heated by gas, it is also 40 of value where the melting is accomplished by electricity. In the latter case, of course, the standard 12 may be solid.

I have also provided a hook 39 on the neck of the ventilating head for the purpose 45 of removably supporting a thermometer 40. The hook is of course so located that the thermometer, when supported thereon, dips at its lower end into the molten metal in the pot. The operative is thus able to ascertain 50 at any time the heat of the metal, and be sure that it is in proper working condition. This is a practical feature of great importance, since the proper operation of the casting mechanism is dependent upon the proper 55 condition of the metal in the pot.

Various modifications in detail of arrangement and modification and construction of parts will readily occur to those dealing 60 with the subject, without departing from what I claim as my invention.

I claim—

1. The combination with a type-metal melting pot, of a standard supported thereon and arranged at one side of the pot, a ventilating head on said standard, a collecting

70 conduit swivelling on said head and extending therefrom over the pot to collect the fumes rising therefrom, and means at the swivel joint holding said conduit in fixed position over the pot.

2. The combination with a type-metal melting pot, of a standard supported thereon and arranged at one side of the pot, a ventilating head on said standard, a collecting 75 conduit swivelling on said head and extending therefrom over the pot to collect the fumes rising therefrom, and cam means at the swivel joint holding said conduit in fixed position over the pot.

3. The combination with a type-metal melting pot, of a standard supported thereon and arranged at one side of the pot, a ventilating head on said standard, a collecting conduit swivelling on said head and extending therefrom over the pot to collect the fumes rising therefrom, a handle projecting from said conduit to facilitate its rotation on the ventilating head, the portion 80 of the conduit below the said handle comprising telescoping sections to permit the cover section to be raised above the level of the pot.

4. The combination with a type-metal melting pot, of a standard supported thereon and arranged at one side of the pot, a ventilating head on said standard, a collecting conduit swivelling on said head and extending therefrom over the pot to collect the fumes rising therefrom, a handle projecting from said conduit to facilitate its rotation on the ventilating head, the portion 90 of the conduit below the said handle comprising telescoping sections to permit the cover section to be raised above the level of the pot, and a stud and hook engagement between the telescoping parts by which the lower section may be supported while the conduit is rotated by means of said handle.

5. The combination with a type-metal melting pot, of a ventilator comprising an open-ended collecting conduit adapted to be positioned over the pot to collect the fumes rising therefrom and terminating at its upper end in a cone-shaped sleeve, together 110 with a cone-shaped ventilating head to which said conduit opens and with relation to which said sleeve swivels, and a manually operated cam ring for securing said sleeve against rotation with respect to said head.

6. The combination with a type-metal melting pot, of a ventilator comprising a jacket surrounding the pot and having a port, a hollow standard rising from said port, an apertured ventilating head on said 125 standard, a sleeve swivelling on said head, a conduit carried by said sleeve and opening to said head at one end, its other end being positioned over the top of said pot to collect the fumes rising from the latter.

7. The combination with a type-metal melting pot, of a ventilator comprising a jacket surrounding the pot and having a port, a hollow standard rising from said port, an apertured cone-shaped ventilating head on said standard, a cone-shaped sleeve swivelling on said head, a conduit carried by said sleeve and opening to said head at one end, its other end being positioned over the top of said pot to collect the fumes rising from the latter.

8. The combination with a type-metal melting pot, of a ventilator comprising a jacket surrounding the pot and having a

port, a hollow standard rising from said port, an apertured cone-shaped ventilating head on said standard, a cone-shaped sleeve swivelling on said head, a conduit carried by said sleeve and opening to said head at one end, its other end being positioned over the top of said pot to collect the fumes rising from the latter, together with a cam ring for securing said sleeve against rotation with respect to said head.

In testimony whereof I have signed my name to this specification.

EMILE D. KRIEG.
